H. A. BERENDSEN

FOLDING STOCKING STRETCHER

Filed April 25, 1922

UNITED STATES PATENT OFFICE.

HENRY A. BERENDSEN, OF BANGOR, PENNSYLVANIA.

FOLDING STOCKING STRETCHER.

Application filed April 25, 1922. Serial No. 556,375.

To all whom it may concern:

Be it known that I, HENRY A. BERENDSEN, a citizen of the United States, and a resident of Bangor, in the county of Northampton and State of Pennsylvania, have invented a new and Improved Folding Stocking Stretcher, of which the following is a full, clear, and exact description.

This invention relates to stocking stretchers and particularly to an improved folding stretcher which when unfolded presents a proper form on which a stocking may be positioned for stretching and drying and when not in use may be folded to a compact body and easily stored away.

The object of the invention is to provide a strong, simple construction which may be quickly folded without injury at any time.

Another object of the invention is to provide a stretcher for stockings which may be folded and unfolded at any time and which may be adjusted to accommodate different size stockings.

In the accompanying drawing—

25 Figure 1 is a plan view of a stretcher disclosing one embodiment of the invention.

Figure 2 is an edge view of the structure shown in Figure 1, the toe member being removed.

30 Figure 3 is an enlarged plan view showing one of the sliding clamps and joints forming certain features of the invention.

Figure 4 is a sectional view through Figure 3 on line 4—4.

35 Figure 5 is a sectional view through Figure 1 on line 5—5.

Referring to the accompanying drawing by numerals, 1 indicates a top section, 2 a central section and 3 a foot section forming 40 the complete stretcher when used for a given size stocking. When it is desired to use the device for larger stockings than a certain size, an adjustable toe member 4 is provided said adjustable member being prefer-

45 ably formed from sheet metal with the ends bent over for forming gripping members 5 and 6 which grip the upper and lower bars of the section 3. The toe section 4 is provided with any desired number of openings

50 7 to lighten the structure without interfering with its proper operation.

As shown in Figure 1, the toe section 4 causes the stretcher to accommodate a stocking one size larger than it would accommodate without this toe section. If a second size larger was to be used on the stretch-

er, the toe section 4 would be moved out a proper distance and in that way a proper foot member would be provided for the foot of the stocking.

If it should be desired to use the device without the toe section 4, said section may be readily slid off the end by a pull and then the foot section 3 would be ready to receive the smaller size stocking of which the

stretcher is ready to accommodate. It will be noted that the sections 1, 2 and 3 are made from wire or round bars and said sections are connected together in such a manner that section 3 may be folded to a position

70 on top or partially within section 2 and then section 1 may be folded over or on top of these two sections. The articulated end of section 3 is provided with one complete turn or loop 8 which merges into an

75 extension 9 adapted to receive one jaw of the clamp 10, the opposite jaw of said clamp being slidingly mounted on the front rod 11 of section 2. The clamp 10 as shown in Figures

3 and 4 is provided with jaws 12 and 13 which are substantially tubular though positioned to resiliently grip section 11 and also the extension 9 when in operative position.

The opposite side of the articulated end 85 of section 3 to that having the loop 8 is merely bent at 14 and extends to a central line of the section where it is formed with a bent up end portion 15 preferably touch-

90 ing the bent up end section 16 of the portion or bent pintle member 17, which portion or pintle member is an extension from the front rod 11, said front rod being bent at 18 and extending through loop 8. The rear rod 19 of section 2 is provided with

95 a loop 20 similar to loop 8, said loop 20 merging into an extension 21 for en-

gaging one of the jaws of the sliding clamp 22 which clamp is identical with clamp 10 but slides back and forth on the rod section

100 23 of the foot section 3. When these clamps 10 and 22 are in position as shown in Figure 1, the sections 2 and 3 are held rigidly in alignment.

The upper end of rod 11 is bent at 24 105 for forming the inwardly extending portion or bent pintle member 25 merging in the projection 26 preferably engaging the projection 27 of the portion or bent pintle member 28, said portion or bent pintle mem-

110 ber 28 being part of the rear rod 29, said rear rod being bent at 30 for forming the

portion 28. The front rod 31 of section 1 is provided with a loop 32 similar to loop 8, said loop merging into a projection 33 for engaging one of the jaws of the 5 clamp 10' which clamp is identical with clamp 10. The rear bar or rod 19 of section 2 is provided with a turn or loop 34 similar to the turn or loop 8, said loop merging into an extension 35 for receiving one jaw of the clamp 22' which clamp 10 is identical with clamp 10.

It will be noted that all of the clamps are identical for holding the respective sections rigidly in alignment when the device 15 is to be used. When it is desired to fold the device and store the same out of the way, as for instance, in a satchel, clamps 10 and 10' are moved towards each other until they release the extensions 9 and 33 20 while clamps 22 and 22' are forced away from each other until they slide off the extensions 21 and 35. The sections may then be folded and the stretcher disposed of. This folding of the stretcher is very 25 desirable where a lady is traveling from place to place as it may be stored away in one of her grips without trouble.

What I claim is:—

1. A folding stocking stretcher, comprising 30 a foot section, a plurality of leg sections, said sections being hingedly connected together, and means for clamping said sections rigidly in alignment.

2. A folding stocking stretcher, comprising a plurality of sections, each section 35 having a bent pintle member and a loop, the pintle member of one section extending through the loop of the other section whereby said sections are pivotally connected together, and means arranged adjacent each 40 pivotal connection movable into a position for holding the sections rigidly in alignment when the stretcher is to be used.

3. A folding stocking stretcher, comprising 45 a metallic wire body formed into three sections, each of said sections being formed with hinge connecting members interacting with the next adjacent sections whereby said sections may be arranged in alignment or folded, each of said sections having projections at the interacting parts, and a sliding clamp for each projection, said sliding clamps being mounted on the respective sections and adapted to slide over the 50 projections of the next adjacent sections for holding the sections rigidly in alignment.

4. In a stocking stretcher, a body merging 55 into a foot formed with top and bottom bars, and a removable toe section formed with turned over edges acting as resilient clamping members engaging said top and bottom bars, said toe section being slideable along said bars for varying the effective length of the foot of the stretcher.

HENRY A. BERENDSEN.
